REMOTE CONTROL LIGHT CONTROL
DEVICE

Ferdinand Chanoux, Elmhurst, Long Island, N. Y.

Application June 22, 1946, Serial No. 678,708

4 Claims. (Cl. 74—469)

1

This invention relates to control mechanisms for electric devices and more particularly to mechanical mechanisms for operating an electric device from a remote point.

It is an object of the present invention to provide a mechanical system composed of units which can be disposed upon ceiling wall surfaces in any number to readily provide a control point at any one of several locations removed from the electric device being operated and through which connections with other operating mechanisms may be made upon being led back in its connection with the electrical device.

It is another object of the present invention to provide a simple device containing an electric lamp and means adapted to be connected with the pull chain of the lamp in such manner that the operating devices remote from the lamp will be returned to their inoperative positions automatically upon being released by the main device at the lamp.

According to the present invention, the lamp or electrical device is mounted on a casing containing a disc adapted to be rotated therewithin by a control device extending into the casing from remote points and linked therewith. This disc is automatically returned by a flat coil spring when the remote devices are released. This spring not only serves to position the disc within the casing but serves to position the control elements and linkages located at positions removed from the lamp.

Within the casing and below the disc is a pulley element over which a chain adapted to operate the lamp is extended. As the disc is rotated against the action of the spring, the pull chain is wound upon the pulley element and the lamp is turned on or off. Upon release of the operating devices the disc is returned to its normal position and the chain is unwound from the pulley element. The operating devices remote from the lamp comprise a similar arrangement of a casing and a disc therewithin adapted to be operated by rods entering the casing from any one or more angular positions. This casing with the disc can be located on a ceiling or upon a side wall and still be arranged so as to receive the interconnecting operating rods.

For further comprehension of the invention, and of the objects and advantages thereof, reference will be had to the following description and accompanying drawings, and to the appended claims in which the various novel features of the invention are more particularly set forth.

2

In the accompanying drawings forming a material part of this disclosure:

Fig. 1 is a plan view looking upon the ceiling of a room employing the lamp device and the mechanical operating mechanism to the present invention.

Fig. 2 is an elevational view looking upon the lamp device and the operating mechanism upon the wall of the room.

Fig. 3 is a cross sectional view of the device and mechanism taken along the line 3—3 of Fig. 2 looking in the direction of the arrows thereof.

Fig. 4 is a cross sectional view, in elevation, taken through the device and mechanisms as viewed along the line 4—4 of Fig. 3 looking in the direction of the arrows thereof.

Fig. 5 is an enlarged fragmentary and cross sectional view of the lamp device and the spring operated disc mechanism for operating the lamp.

Fig. 6 is a cross sectional view looking upon the top of the operating disc of the lamp device, taken along the line 6—6 of Fig. 5 looking in the direction of the arrows thereof.

Fig. 7 is a cross sectional view of one of the remote operating mechanisms to which the operating rods are connected.

Referring now to the figures, 12 represents a lamp device which is to be operated by the control mechanism of the present invention. This lamp device comprises a large casing 13 having on its bottom 14 a socket 15 containing a lamp bulb 16. Through the socket 15 there is extended the usual chain 17 for effecting the rotation of the switch operating mechanism within the socket. As the chain is pulled out, the lamp is either turned on or off and upon release of the chain the same is returned to the socket by mechanism therewithin. The casing 13 includes a base 18 (Fig. 5) by which attachment of the casing is made with a ceiling 19 of a room to be lighted. The electrical connections with the socket 15 may be made through the casing 13 or externally thereof in any well known manner.

Depending from the base 18 is a pivot stud 21 on the lower end of which there is journaled or steadied, a large disc 22 having screw eyes 23 thereon located ninety degrees apart. A flat coiled spring 26 is adapted to counteract an operating rod or cable 24 anchored to the stud 21, and is indirectly connected thereto as indicated at 25 (Fig. 6) and is connected at its other end 27 to the top of the disc 22 whereby upon a pull of the rod 24, the spring will be wound about the stud. The spring will return the disc 22 to its normal position upon release of the rod 24. The

rod 24 may extend through any one of four holes 28 in the casing located ninety degrees apart. Thus the rod can be extended through the casing from any one of four directions or from all four of the directions at one time depending upon the number of remote control stations it is desired to have.

Upon the bottom of the disc 12 is a pulley element 29 out of which there downwardly extends a supporting stud 31 for the disc which is journaled in the bottom 14 of the casing 13. On the bottom 14 there are extended upwardly, spaced lugs 32 between which is trunnioned a pulley pinion 33 over which the chain 17, upon entering the casing 13 through an opening 34, is extended to change its direction for connection with the pulley element 29. As the disc 22 is rotated by the rod, the chain 17 is wound upon the pulley element 29 to take up the slack in the chain 17 and pull it from the socket 15 to either turn on or turn off the lamp bulb 16. As the rod 24 is released, the chain 17 will be unwound from the pulley element 29 so that the chain is returned to the socket 15 and ready to be operated or pulled again.

The rod 24 upon passing through the opening 28 may extend to a second disc device 35 comprising a casing 36 in which there is journaled a disc 37 (Fig. 7) in much the same manner as the disc 22 is journaled in the casing 13. A stud 38 depends from a base 39 and has the disc 37 journaled on its lower end. The disc 37 has a stud 41 journaled in the bottom of the casing 36 and is supported against vertical thrust in a socket portion 42 thereof. Depending from the disc 37 are screw eyes 43 to which the rod 24 and other rods 44 may be connected upon entering the casing 36 through any one of openings 45 thereof.

If a change in the direction of pull of the rods is desired the device 35 may be connected with its base 39 upon a vertical wall surface, as indicated at 46. Then a rod 47 may extend in a downward direction within reach of a person stationed in the room and desiring to use the lamp. If the rod 47 is pulled downwardly, the disc 37 within the device 46 is rotated through ninety degrees and in turn the rod 44, connected with the device 46, is moved axially to pull or rotate the disc 37 of the device 35 which is in turn connected through the rod 24 with the main disc 22 which, through the pulley element 29, effects a pulling of the chain 17 and the operation of the lamp 16. As a grip is released from the rod 47 all of the connecting elements are returned to their original position by the coil spring 26 of the lamp device 12. Other devices 35 containing the discs 37 can be connected at any number of locations within the room and by means of rods connected through devices 35 with the main device 12 or connected to the device 12 from another angle or direction therefrom. The same common spring 26 will return all of the devices and the rods to their inoperative positions.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent, is:

1. A mechanical operating mechanism for an electrical device comprising a disc device having a casing for positioning of sockets for an electrical device thereon adapted to be operated and removed therefrom, a rod connected to said device and adapted to be pulled to effect its operation, said device comprising a casing with openings through which rods can be extended, a disc pivoted within the casing for rotation through ninety degrees as the rod is pulled, and means for fastening the rods to the disc, said electrical device having a part adapted to be pulled, means for connecting the part with a disc of the device, and a spring connected to the disc of said device for returning said disc to its inoperative position when it has been released after having effected the operation of the electrical device.

2. A mechanical operating mechanism for an electrical device comprising a disc device having a casing for positioning of sockets for an electrical device thereon adapted to be operated and removed therefrom, a rod connected to said device and adapted to be pulled to effect its operation, said device comprising a casing with openings through which rods can be extended, a disc pivoted within the casing for rotation through ninety degrees as the rod is pulled, and means for fastening the rods to the disc, said electrical device having a part adapted to be pulled, means for connecting the part with a disc of the device, and a spring connected to the disc of said device for returning said disc to its inoperative position when it has been released after having effected the operation of the electrical device, said connecting means between the electrical device and the disc comprising a pulley element mounted on the disc and adapted to be operated by the same, whereby to pull the electrical device part to an operative position, the said electrical device part being in the form of a flexible pull element adapted to be wrapped about the pulley.

3. A mechanical operating mechanism for an electrical device comprising a disc device having a casing for positioning of sockets for an electrical device thereon adapted to be operated and removed therefrom, a rod connected to said device and adapted to be pulled to effect its operation, said device comprising a casing with openings through which rods can be extended, a disc pivoted within the casing for rotation through ninety degrees as the rod is pulled, and means for fastening the rods to the disc, said electrical device having a part adapted to be pulled, means for connecting the part with a disc of the device, and a spring connected to the disc of said device for returning said disc to its inoperative position when it has been released after having effected the operation of the electrical device, said connecting means between the electrical device and the disc comprising a pulley element mounted on the disc and adapted to be operated by the same, whereby to pull the electrical device part to an operative position, the said electrical device part being in the form of a flexible pull element and adapted to be wrapped about the pulley, said electrical device being mounted on the casing of one of the operating devices, an opening in the casing, said flexible pull element extending through the opening, a small pulley above the opening and serving to permit a change in the direction of the flexible pull element upon being extended about the pul-

ley element, and supporting brackets within the casing in which the small pulley is pivoted.

4. A mechanical operating mechanism for an electrical device comprising a disc device having a casing for positioning of sockets for an electrical device thereon adapted to be operated and removed therefrom, a rod connected to said device and adapted to be pulled to effect its operation, said device comprising a casing with openings through which rods can be extended, a disc pivoted within the casing for rotation through ninety degrees as the rod is pulled, and means for fastening the rods to the disc, said electrical device having a part adapted to be pulled, means for connecting the part with a disc of the device, and a spring connected to the disc of said device for returning said disc to its inoperative position when it has been released after having effected the operation of the electrical device, said connecting means between the electrical device and the disc comprising a pulley element mounted on the disc and adapted to be

operated by the same, whereby to pull the electrical device part to an operative position, the said electrical device part being in the form of a flexible pull element and adapted to be wrapped about the pulley, said spring being of the flat coil type and mounted on the side of the disc opposite to the side of the disc on which the pulley element is mounted, said electrical device being mounted on the casing of one of 10 the disc operating devices.
